UNITED STATES PATENT OFFICE.

JOHN FRANKLIN BLANCHARD, OF NEW YORK, N. Y.

REVOLVING SASH.

SPECIFICATION forming part of Letters Patent No. 762,123, dated June 7, 1904.

Application filed November 22, 1902. Serial No. 132,391. (No model.)

To all whom it may concern:

Be it known that I, JOHN FRANKLIN BLANCHARD, a citizen of the United States, and a resident of the city of New York, borough of Manhattan, in the county and State of New York, have invented a new and Improved Revolving Sash, of which the following is a full, clear, and exact description.

My invention relates to revolving window-sashes, my more particular object being to produce an efficient form of revolving sash admitting of general use and possessing certain advantages hereinafter set forth.

Reference is to be had to the accompanying drawings, forming a part of this specification, in which similar characters of reference indicate corresponding parts in all the figures.

Figure 1 is a perspective view showing my invention as applied to a window. Fig. 2 is a section upon the line 2 2 in Fig. 4 looking in the direction of the arrow. Fig. 3 is an elevation of one member of the auxiliary stile, the other parts being removed; and Fig. 4 is an enlarged section upon the lines 4 4 in Fig. 3 looking in the direction of the arrow.

The stiles are shown at 1, the glass at 2, the fastenings therefor at 3, and the upper and lower rails at 4 and 5. Mounted within each stile 1 is a trunnion-plate 6, provided with screws 7 8 for holding the same in position and also provided with trunnions 9, integral therewith. A longitudinal groove 10 is provided in the edge of each stile and of each trunnion-block 6, this groove being continuous throughout the entire length of the stile.

The window-facing is shown at 11 and is provided with a channel 12. A chain or equivalent suspending device 13 is provided for sustaining the weight of the sash in the usual manner. This chain preferably engages the trunnions 9, as indicated more particularly in Fig. 2. An auxiliary stile made in two parts 14 16 is fitted partially into the channel 12, the part 14 being of the shape indicated in Fig. 4 and being provided with flanges 15. The part 16 fits telescopically upon the part 14, as indicated more particularly in Fig. 4. This part 16 is provided with a longitudinal bead 17, which engages the groove 10. Leaf-springs 18 are mounted upon the part 16 by

means of rivets 19, these springs normally pressing against the flanges 15. Pins 20 are secured rigidly upon the part 16 and pass loosely through holes 20^a. (Shown to better advantage in Fig. 3.) Each trunnion 9 removably engages a bearing-block 22, held in place by fastenings 23 and provided with a trunnion-hole 24, as indicated more particularly in Figs. 2 and 3, and also engages a somewhat similar bearing-block 22^a, rigidly connected with the auxiliary stile 16, as shown more particularly in Figs. 2 and 4.

The members 14 are each provided with a slot 25, as shown more particularly in Fig. 3, for permitting the use of a side pulley in the usual manner.

Each stile 1 is provided with a hole 26, in which is mounted a cylindrical spring 27 and a pin 28, the pin having a limiting-stop 29. The pin passes through a hole 30 in the bead 17 and is provided with a knob 31 for convenience in manipulation. When the knob 31 is drawn inwardly, the spring-pin is withdrawn from engagement with the bead 17, and the sash may be moved, as indicated in Fig. 1. When the sash is vertical, the pressure of the leaf-springs 18, by causing one portion 16 of the hollow casing to move asunder from the other portion thereof, forces the bead 17 into the groove 10, thereby causing the sash to snap into its normal position. The spring-pin 28 is moved slightly to the left when the window snaps into position, the inner end of the pin traveling over the rounded surface of the bead 17 until the hole 30 is reached, whereupon the pin 28 snaps into the position indicated in Fig. 2. The sash is therefore doubly locked, being held not only by the bead 17 engaging the groove 10 under pressure of the leaf-springs 18, but being further held by the spring-pin 28 engaging the hole 30. When the sash is turned at an angle to its normal position, as indicated more particularly in Fig. 1, the outer portion 16 of the stile is forced toward the window-facing 11, the two parts 16 and 14 thereby having a sort of telescopic action, which will be readily understood from inspection of Fig. 4. The guide-pins 20 maintain these parts in proper relation, while permitting the slight lateral movement necessary of

the member 16. Under no conditions can the member 16 be pressed so far to the left or toward the center of the window as to disengage the two parts of the auxiliary stile, for 5 the reason that the sash 1 is centered by the extension of the pivots 9 and is therefore comparatively free from lateral movement regardless of the action of any other part. In other words, the sash 1 would be held centrally by the pivots 9 even if the springs and 10 the pins were removed entirely.

The bead 17 serves as a weather-strip, effectively excluding the passage of cold and moist air.

15 Having thus described my invention, I claim as new and desire to secure by Letters Patent—

1. A revoluble sash comprising a stationary window-frame provided with a channel, a metallic auxiliary stile fitting into said channel 20 and made in two parts telescoping each other, one of said parts having flanged edges provided with holes, the other of said parts being provided with pins engaging said holes, springs for normally maintaining said parts 25 in predetermined positions relatively to each other, and a revoluble sash member for engaging one of said parts of said stile and being temporarily held in a predetermined position by the pressure of said stile thereon.

2. In a revolving sash, the combination of 30 a stationary window-frame provided with a channel, a metallic auxiliary stile fitting into said channel and made in two parts telescoping each other, one of said parts having flanged edges, means for guiding the movements of said two parts telescoping each other, 35 springs for normally maintaining said parts in predetermined positions relatively to each other, and a revoluble sash member for engaging one of said parts of said stile, said 40 revoluble sash being normally held in place by the pressure of said stile thereon.

3. In a revoluble sash, the combination of 45 a stationary window-frame provided with a channel, an auxiliary stile slidably mounted within said channel and provided with bearings, a revoluble sash member provided with a trunnion for engaging said bearings, and a longitudinal flexible member engaging said trunnion and coacting with said bearings as a 50 pivotal support for said trunnion.

In testimony whereof I have signed my name to this specification in the presence of two subscribing witnesses.

J. FRANKLIN BLANCHARD.
